UNITED STATES PATENT OFFICE.

ORANGE S. CONKLIN, OF JERSEY CITY, NEW JERSEY.

SIGNAL-LAMP.

SPECIFICATION forming part of Letters Patent No. 536,603, dated April 2, 1895.

Application filed September 14, 1894. Serial No. 522,973. (No model.)

To all whom it may concern:

Be it known that I, ORANGE S. CONKLIN, of Jersey City, Hudson county, New Jersey, have invented an Improved Signal-Lamp, of which 5 the following is a specification.

This invention relates to a railway signal lamp embodying various features of improvement, such as an improved air supply, an improved top, and an improved reflector, by 10 which the rear light may be put into or out of action.

In the accompanying drawings: Figure 1 is a vertical section of my improved lamp on line 1, 1, Fig. 6. Fig. 2 is a similar section on line 15 2, 2, Fig. 6; Fig. 3, a rear view of the reflector; Fig. 4, a plan, showing the reflector connected to the back light; Fig. 5, a vertical central section through a modification of the lamp top; Fig. 6, a horizontal section of the lamp, 20 on line 6, 6, Fig. 1, and Fig. 7, a similar section on line 7, 7, Fig. 1.

The letter a , represents the body of a signal lamp made of suitable form and designed for any of the various uses to which railway 25 lamps are put. Above the bottom a' , of the lamp, I arrange a false bottom a^2 , upon which the oil reservoir b , is supported. Between the bottoms a' , a^2 , there is formed an air chamber c , which is supplied with fresh air through a 30 perforation or perforations a^3 , of bottom a' . This perforation may, if desired, be protected and subdivided by a series of spaced parallel wires a^4 , as shown in Fig. 1. Above the perforations a^3 , I secure to the false bottom a^2 , a 35 depending shield or deflector m , beneath which a narrow air passage is formed. This passage connects with the larger end sections of the air chamber c , the object of the deflector being, to break the direct current of air 40 and throw it sidewise, so that flickering will be prevented. Into the enlarged end sections of the chamber c , enter the lower ends of air delivery tubes c' , that are adapted to feed fresh air from the chamber c , to the flame. 45 I employ two inverted U shaped air tubes c' , that connect at both their ends with the chamber c (Fig. 2), and which are placed with their upright shanks within the corners of the lamp (Fig. 6). The perforations c^2 , of the 50 tubes c' are bored at such an angle, as to face outwardly and to conduct the air, not directly to the flame, but toward the sides of the lamp,

as indicated by the arrows in Fig. 6. In this way, the flame is supplied with air from all sides, and at the same time flickering is prevented. I have found that by this construction of air supply, the lamp is kept perfectly cool for an indefinite period of time, and thus a very desirable object is attained.

The side walls of the deflector m , are perforated, so that a current of fresh air circulates through the chamber formed by said deflector and the false bottom a^2 . In this way the oil reservoir b , is cooled and overheating 60 of the oil is prevented.

d , is the front lens or semaphore, and e , the back lens which is secured within the center of the annular frame e' and directly opposite the lens d . To the inner side of this frame is connected a reflector f , for increasing the 70 volume of light emitted through the semaphore d . This reflector is so constructed, that the back light may by it, be shut off or exposed, and thus the lamp may be readily converted from a single light lamp, into a double 75 light lamp. To effect this result the reflector f , is provided with a small central perforation f' , that forms the mouth of a rearwardly extending flaring tube f^2 . This tube carries at its free end a head f^3 , adapted to engage a 80 pair of converging rails e^2 , connected to the back of lens frame e' , at the sides of lens e , (Figs. 2 and 4.) To attach the reflector to the lamp, its head f^3 , is slipped downward between the rails e^2 , while a reverse motion will 85 disconnect the reflector, as will be readily understood. The tube f^2 , is provided with a transverse slit f^4 , adapted for the passage of a lid or shutter f^5 , pivoted to an arm f^6 , of the tube. The opening f' , and tube f^2 , are in 90 line with the lens e , and thus when the lid is swung across the tube, it will shut off the light from the lens and extinguish the back light, but when the lid is swung up to clear the tube, the light is free to pass to the lens, so 95 that the back light will show. In this way the back light can be quickly turned on or off.

The top of the lamp is composed of an outer cylindrical shell g , and an inner shorter conical shell g' , connected to a joint corrugated 100 roof g^2 , so as to leave an air outlet below the roof. The lamp body is provided with the upwardly projecting short conical tube a^5 , that flares toward its upper end. This tube enters

the mouth of the conical tube g' , (Fig. 1) which flares toward its lower end and forms a tight joint with the tube a^5 . The tubes a^5, g' , jointly constitute a central exit flue for the hot gases and products of combustion. These gases pass through the open roof a^6 , of the lamp body, and thence through the tubes a^5, g' , and out beneath the roof g^2 . The outer cylinder g , is perforated at its lower end as at g^3 , for the admission of fresh air, which is drawn up into the annular space g^4 , and thence out beneath the roof g^2 . The current of cool air is induced by the flow of the heated gases, and will serve to increase the draft and also to cool the lantern top.

In Fig. 5, the outer cylinder g , is connected to the roof g^2 , by an open lap joint g^5 , by which any possibility of a back draft is avoided. It will be seen that my improved lamp is supplied with an abundant quantity of fresh air which furnishes oxygen for a perfect combustion. Thus the wick will not carbonize and the lamp will remain cool without regard to the period of time during which it has remained lighted.

What I claim is—

1. The combination in a signal lamp, of a perforated bottom with an upper false bottom to form an air chamber, a deflector within said chamber above the perforations, and with upwardly extending perforated tubes that enter

the enlarged end sections of the air chamber and deliver the air into the body of the lamp, substantially as specified.

2. The combination in a signal lamp, of a front lens with a back lens placed in alignment therewith, a burner between the lenses, a perforated reflector between the burner and the back lens, a slotted conical tube projecting rearwardly from the reflector, and a shutter pivoted to said tube and adapted to engage the slit, substantially as specified.

3. The combination in a signal lamp, of a back light with a retaining frame, a pair of rails secured thereto, a perforated reflector, a tube secured thereto, a head secured to the tube and adapted to engage the rails, and with a shutter adapted to be projected across the tube, substantially as specified.

4. The combination in a signal lamp, of a conical inner tube g' , with a roof having an inwardly and upwardly curled lower edge, a conical tube a^5 , that enters the tube g' , and a perforated outer tube having an outwardly and downwardly curled upper edge, that forms an open lap joint with the roof, substantially as specified.

ORANGE S. CONKLIN.
